UNITED STATES PATENT OFFICE.

MILLARD VON HALLE, OF PALISADES PARK, NEW JERSEY, ASSIGNOR TO THE STANDARD CORSET COMPANY, OF NEW YORK, N. Y., A CORPORATION OF MASSACHUSETTS.

ART OF SEWING.

Application filed April 13, 1927. Serial No. 183,359.

This invention relates to the art of sewing, and has for its main object and features a method whereby disks of relatively rigid material may be secured in position between layers of flexible material by sewing.

In the accompanying drawings the invention is disclosed in a concrete and preferred form in which

Fig. 1 is a perspective view of a sewing machine head and associated elements embodying the invention.

Fig. 2 is a plan view, with parts broken away and in section, of the parts shown in Fig. 1 with material shown in position and being acted upon.

Fig. 3 is a detail plan view of a modified form of the invention.

In order to stiffen certain flexible material, such as that which is used in corsets, it is, at 20 times, desirable to use stiffening means other than the conventional "boning" consisting of flat strips. I purpose to use disk-like members such as A which are placed between two or more layers of flexible material such as 12 and 12^a. The disk is provided with an opening a at its center and the layers of flexible material are provided with corresponding openings and preferably a gromet or eyelet a¹ is used to initially secure the disk and flexible material together. B indicates a sewing head having here needle 10, presser foot 10^a and feeding means 11. Adjacent needle 10 and parallel thereto is a post 14 constituting a pivot or center that is passed through the eyelet aforesaid, and this post is spaced from the needle a distance somewhat greater than the radius of the disk. When the flexible material is now placed in position on sewing table 13 and in operative relation to the sew-

ing head, the needle of the latter will stitch 40 the two layers together circumferentially around the disk, as at B¹, to thereby confine said disk between the layers of flexible material. During this action the disk and material turn on pivot 14 and all danger of needle 45 10 striking the disk is avoided.

The post may be secured to the sewing machine in any suitable way. Preferably a plate as 1 is provided carrying said post, and this plate is provided with an L-shape extension 2 through which passes a set-screw 3 which may enter an opening 4 in the sewing table. Plate 1 is further provided with a dependent flange 5 that extends into a slot 6 cut in recess 7 usually found in sewing machines and which recess is covered by slide 9 in the usual way. When screw 3 is tightened and slide 9 is in position, plate 1 is held rigidly and against displacement. To provide for different size disks different members like 1 with parts 14 may be provided, or, as shown in Fig. 3, a plurality of openings 15 may be employed into any one of which post 14 may be secured.

I claim:

The method of securing a disk, interposed between layers of flexible material, to said material which consists in: initially attaching the layers of material and disk together with an eyelet at the center of the disk, mounting the disk and layers on a pivot adjacent a sewing head, and then subjecting the layers of flexible material to the action of said sewing head to sew the layers together circumferentially around the disk.

Signed at the borough of Manhattan, city 75 county and State of New York, this 11 day of April 1927.

MILLARD VON HALLE.
